UNITED STATES PATENT OFFICE.

JOHN W. SLACK, OF SILVER CREEK, NEW YORK, ASSIGNOR TO COLUMBIA POSTAL SUPPLY COMPANY, OF SILVER CREEK, NEW YORK, A CORPORATION OF NEW YORK.

CANCELING DEVICE.

1,401,742.

Specification of Letters Patent. Patented Dec. 27, 1921.

Application filed May 15, 1920. Serial No. 381,673.

To all whom it may concern:

Be it known that I, JOHN W. SLACK, a citizen of the United States, residing at Silver Creek, in the county of Chautauqua 5 and State of New York, have invented new and useful Improvements in Canceling Devices, of which the following is a specification.

This invention relates to a canceling device for printing mail matter either with 10 ruling lines or with a post mark or date.

One of the objects of this invention is the production of a canceling device of this character which is more particularly designed 15 for marking parcel post packages without damaging the same as is the case when employing an ordinary hand stamp.

Another object of this invention is to provide a device which is operated by an easy 20 rolling action and which will produce an imprint on the mail matter without requiring undue pressure and tiring the operator.

This invention has the further object to provide a canceling device which will readily 25 adapt itself to any uneven surfaces and produce a good impression of the printing element thereon.

Additional objects are to produce these results by means which are of simple, efficient 30 and durable construction and capable of being manufactured at low cost.

In the accompanying drawings:

Figure 1 is a side elevation of a canceling device embodying my invention, partly 35 broken away, and constructed to produce both canceling or ruling lines and also a post or date mark on the mail matter. Fig. 2 is a top plan view of the same, partly broken away. Fig. 3 is a vertical longitudinal section of the same, on line 3—3, Fig. 40. Figs. 4, 5 and 6 are vertical transverse sections taken on the correspondingly numbered lines in Fig. 3. Fig. 7 is a face view of the printing wheel having a post marking die and canceling ribs. Fig. 8 is a vertical longitudinal section of a canceling device designed for producing, canceling or 45 ruling lines only on the mail matter. Fig. 9 is a plan view of the same, partly in section. Fig. 10 is a vertical cross section taken on line 10—10, Fig. 9.

Similar characters of reference indicate corresponding parts throughout the several views.

Referring to Figs. 1-7, 20 represents the body of the canceling device which is 55 constructed of metal in the form of a hollow casing or housing the underside of which is open.

Within this housing is arranged a printing 60 wheel or roller 21 which projects with its lower operative portion below the casing and is provided on its periphery with any suitable printing surface or type such for instance as circumferential ribs 22 which 65 produce ruling or canceling lines on the object to be marked and a die 23 which carries type representing the post office and the date of mailing and which is removably mounted on the body of the printing wheel, so that 70 the name and date can be changed as desired. This printing wheel is pivotally mounted on the casing by an axle or pin 24 passing axially through this wheel and supported at one end in a plain opening 25 in 75 the casing while its opposite end is provided with a screw thread 26 which engages a threaded opening 27 in the casing. In the use of this canceling device, the printing wheel is rolled over the surface to be printed, 80 thereby producing an impression on the latter. When the printing wheel is organized for post marking and dating the mail matter, it is preferable to limit the rotation 85 of the printing wheel so as to produce but one impression thereof during each stroke. For accomplishing this purpose the printing wheel is provided at one end with a rotatable stop 28 having the form of a lug which is adapted to engage a fixed stop 29 having the 90 form of a screw arranged on the adjacent wall of the casing. By this means the printing wheel is capable of making nearly one rotation in either direction by reason of the rotatable stop 28 engaging one side or the 95 other with the fixed stop 29.

In order to permit of operating the canceling device so that a printing impression is produced by a stroke in one direction and the printing wheel is automatically returned 100 to its initial position upon lifting canceling device, a coil spring 30 is provided which

is placed around the axle within the printing wheel and connected at one end with the axle and at its opposite end with the printing wheel. The organization of the parts is 5 preferably such that a printing impression is produced by pushing the casing forwardly with the printing wheel in contact with the mail matter until the rotation of the printing wheel is arrested by the stops and then lifting 10 the device, whereupon the printing wheel is automatically returned by the spring 30 which has been wound up during the forward rotation of the printing wheel.

Any suitable means may be provided for 15 inking the impression or type surfaces of the printing wheel, but those shown in the drawings have been found satisfactory in practice and are constructed as follows:

31 represents an ink supply roller having 20 a body of felt or similar absorbent material and arranged transversely within the casing in rear of the printing wheel. This ink supply roller is journaled on a pin 32 secured transversely to the walls of the casing 25 and ink is supplied to the same through an opening or slot 33 formed in the top of the casing below which the supply roller is arranged and is visible therethrough while the device is in its operative position. Means 30 are provided for taking the ink from the supply roller, mixing and distributing the same and delivering the same to the printing surface of the printing wheel. These means in their preferred form comprise two delivery or transfer rollers 34, 35, which engage with opposite sides of the ink supply roller and the printing wheel and are held 35 yieldingly in engagement therewith by two pairs of links 36 connected with opposite 40 ends of the axles 37, 38 on which the delivery rollers are mounted, and two springs 39 connecting the corresponding links at opposite ends of the delivery rollers. These means of transferring the ink are very 45 simple in construction and efficient in operation and readily adapt themselves to the surfaces with which the same coöperate, and the same can also be quickly and conveniently assembled and dismembered.

50 In order to permit of producing a uniform impression of the canceling device when running the same over uneven surfaces such as parcel post packages usually present, the handle 40 for operating the 55 canceling device is connected at its front end with the rear end of the casing or body by a swivel joint which permits the casing, printing wheel and associated parts to rock transversely independently of the handle, 60 as the printing wheel travels over an uneven surface. The preferred form of joint for this purpose consists of a longitudinal socket 41 arranged on the rear part of the casing and receiving the reduced front 65 shank 42 of the handle, and a screw 43 ar-

ranged on the side of the socket and engaging with a segmental groove 44 formed circumferentially in the periphery of the shank 42 so that the same serve the double purpose of coupling the handle with the casing and also as means for permitting a limited rocking motion of the casing relative to the handle. 70

When the mark, to be placed on an article, is of a fixed or unchanging character, such 75 for instance as the name of a post office, canceling lines or the indorsement form for bank checks, the construction of the device embodying my invention may be organized as shown in Figs. 8, 9 and 10. In this modified construction, the printing wheel or roller 45 is provided with printing ribs 46 which extend all the way around its periphery and no stops are employed, so that continuous ruling or canceling lines or other 80 marks may be printed on a surface. The inking mechanism may also be simplified, as shown in Figs. 8 and 9, in which case the same comprises an inking roller 47 having a felt body engaging the periphery of the 85 printing wheel 45, a U-shaped yoke 48 which carries the spindle or axle 49 upon which the inking roller 47 is journaled, a shank 50 extending rearwardly from the yoke into a recess 51 formed in the front end of the 90 handle, and a spring 52 surrounding the shank 50 within the recess 51 and bearing at one end against the yoke and at its opposite end against the bottom of the recess, thereby holding the inking roller 47 yieldingly in 95 engagement with the printing wheel and permitting the easy removal of the same when required. 100

This canceling device permits of marking or canceling mail matter much more rapidly 105 than is possible by the use of ordinary hand stamps heretofore in use, the same is noiseless, it does far better work without tiring the operator, it is light in weight and the same does not damage mail such as parcel 110 post packages because the canceling device is simply rolled over the package instead of being struck by a blow from an ordinary punch stamp.

The die 23 is connected by a dovetail longitudinal-sliding joint 60 with the periphery of the printing roller and its opposite ends engage with two screws 61, 62 on this roller, whereby the same is held removably in place therein. 115

I claim as my invention.

1. A canceling device comprising a body provided at its rear end with a longitudinal socket, a printing roller mounted on said body, a handle journaled at its front end in said socket and provided in its periphery with a segmental peripheral groove, and a screw secured to said socket and having a reduced inner end engaging with said groove. 125

2. A canceling device comprising a casting, a printing roller journaled in said casting and means for inking said printing roller comprising an ink-supply roller, two floating ink-delivery rollers engaging with said printing and supply rollers on opposite sides of the same, and means for holding

said delivery rollers yieldingly in their operative position, comprising links pivotally connected with opposite ends of said delivery rollers, and springs connecting the corresponding links of said delivery rollers. 10

JOHN W. SLACK.
